(57) **CLAIM**

The ornamental design for a meat thermometer with wireless probe, as shown and described.

DESCRIPTION

FIG. 1 is a front perspective view of a meat thermometer with wireless probe, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view;

FIG. 8 is an enlarged bottom plan view;

FIG. 9 is its state diagram;

FIG. 10 is an enlarged detail view of area 10 in FIG. 2; and, FIG. 11 is an enlarged detail view of area 11 in FIG. 2.

The broken lines in the drawings illustrate the portions of the meat thermometer with wireless probe, which form no part of the claimed design.

The dash-dot-dash broken lines encircling the enlarged views are for annotative purposes only and form no part of the claim thereof.
